UNITED STATES PATENT OFFICE.

PAUL DE SABATO, OF BLAIRSVILLE, PENNSYLVANIA.

DESIGN FOR A WAFFLE-IRON.

51,661.

Specification for Design.

Patented Jan. 1, 1918.

Application filed October 3, 1917. Serial No. 194,622. Term of patent 7 years.

To all whom it may concern:

Be it known that I, PAUL DE SABATO, a citizen of the United States, and a resident of Blairsville, in the county of Indiana and State of Pennsylvania, have invented a new, original, and ornamental Design for a Waffle-Iron, of which the following is a specification, reference being had to the accompanying drawing, forming part thereof, in which—

Figure 1 is a plan view of the inner face of a waffle iron showing my new design, and,

Fig. 2 is an irregular cross section on the line 2—2 of Fig. 1.

I claim:

The ornamental design for a waffle iron, as shown.

PAUL DE SABATO.
